TROUGH BELT

Frederick Robbins, Cambridge, Md., assignor to
The Cambridge Wire Cloth Company, Cam-
bridge, Md., a corporation of Maryland

Application July 26, 1939, Serial No. 286,674

4 Claims. (Cl. 198—201)

My invention relates to conveyors, and has among its objects and advantages the provision of an improved trough conveyor.

In conveyor belts employed for heat treating purposes, it is common practice to employ a metallic belt of the mesh type for handling the materials and articles to be heat treated. Usually, such belts comprise interlaced wires to facilitate passage of heated air therethrough. Such belts are invariably of the endless type and should flex easily about the supporting drums. In some installations, it is necessary to employ a belt capable of making a reverse bend, and the handling of some materials requires that the belt be of the trough type.

An object of my invention is to provide a trough belt designed to bend about the usual supporting drums, wherein the trough belt is characterized by two continuous, upright walls extending along the sides of the belt, and in which the walls are so designed as to permit two-directional bending of the belt without interference from the trough walls.

More specifically, the walls comprise upright plates with the plates arranged partly in overlapping relation to provide the continuous walls. The plates in each wall are pivotally connected together for relative pivotal movement about horizontal axes transversely of the belt, and the pivotal connections comprise wires or rods threaded through some of the interlaced wires of the belt so that each plate in one wall pivots about the same axis as the corresponding plate in the other wall. The rods pivotally connect the plates at their lower, overlapping margins.

Brace members extend transversely of the belt and interconnect certain of the plates in one wall with the corresponding plates in the other wall, so that the overlapping relation between the plates, in combination with the transverse braces, provides a construction in which the two upright walls are effectively restrained from relative lateral deflection. The plates are overlapped in such manner that the transverse braces, even though spaced considerable distances longitudinally of the belt, effectively resist lateral deflection of the individual plates as well as the two walls. While the plates are arranged partly in overlapping relation, the plates and their axes are so arranged as to facilitate bending of the belt in both directions, with the plates overlapping in all phases of the belt.

In the accompanying drawing:

Figure 1 is a perspective view of a portion of a trough belt in accordance with my invention;

Figure 2 is a sectional view along the line 2—2 of Figure 1; and

Figure 3 is a perspective view of two plates from each wall separated for the sake of clearness and illustrating a different form of brace.

In the embodiment selected to illustrate my invention, the belt 12 comprises a plurality of helical wires 14 interlaced into web formation, with the convolutions flattened slightly to take the configuration of ovals when viewed from the end, as illustrated in Figure 2. The ends of the wires are looped together, as at 16 in Figure 1. Belt 12 is provided with upright side walls 18 along its edges, which side walls each comprises a plurality of metallic plates of the type illustrated at 20, 22 and 24. These plates are arranged partly in overlapping relation, as illustrated at 26, and the plates in the two walls are identical in construction and arrangement. Plate 20 partly overlaps the inner face of the plate 22, and plate 22 partly overlaps the inner face of the plate 24. This order of overlapping continues throughout the entire length of the wall.

Wires or rods 28 are threaded through certain of the helical wires 14 and are arranged to pivotally connect the plates in each wall 18. The wires 28 pass through aligned openings 30 in the inside overlapping margins of the plates, centrally of and at the lower ends of the margins, with the lower ends of the plates lying in a plane common to the bottom plane of the belt 12. Thus, one rod 28 pivotally connects two plates in each wall, and the two pivotally connected plates in each wall pivot about an axis corresponding to the axis about which the two corresponding plates in the other wall pivot. Thus, the hinge rods 28 will parallel the axis of the drum about which the belt is flexed so as to eliminate binding, and the overlapping arrangement of the plates provides two continuous walls in which the plate elements thereof pivot relatively to one another as the belt is passing around the drum. Each wall 18 bends easily in either direction because of the overlapping relation between the plates, and the plates are overlapped in such a degree as to maintain some overlapping relation even while the belt is flexing about the drum. Such overlapping relation between the plates provides guiding relation between the overlapped plates when passing from the curved phase to the straight phase so as to eliminate locked edges between the plates.

The ends of the rods 28 are welded at 32 to the outer face of their respective outer overlap-

ping margins. Thus, the plates 20 of Figures 1 and 2 are loosely related to the associated bar 28, with the plates 22 welded to that bar. The plates 20 lie adjacent the side edges of the belt 12 and are therefore restrained from relative movement longitudinally of the bar. At the same time, the plates 20 are restrained from outward movement because of their overlapping relation with the plates 22. This holds true throughout the full length of both walls 18. Accordingly, the ends of the plates 22 overlapping outside the plates 20 are welded to the bar 28, while the opposite ends of the plates 22 which lie inside the plates 24 are loosely related to the second bar 28 in the manner previously described in connection with the plates 20.

Openings 30 in the inside overlapping margins of the plates are fashioned of elliptical contour with their longitudinal axes paralleling the longitudinal axis of the belt. Thus, the plates are so related as to provide continuous walls but are capable of shifting relatively to one another so as to permit the drive roll to take up the slack in the belt. Walls of fixed length along the line of their pivotal connections cause a substantial variation in the amount of friction between the drive roll and the belt during its operation unless the belt is made so as to remain of the same length as the walls at their pivotal line.

At suitable intervals longitudinally of the belt 12 I provide transverse bracing. One such brace is illustrated at 34 in Figures 1 and 2. In the brace structure of Figures 1 and 2, the brace comprises a lower horizontal rod 36 having a right-angled reach 38 at each end which lies adjacent the inner faces of the plates 22 and are welded thereto. The brace also includes a second horizontal wire 40 which has its ends welded to the upper ends of the reaches 38, as at 42. A web 44 of wire mesh has its upper convoluted coil 46 laced over the horizontal rod 40, and the lower coil 48 is laced over the lower rod 36 and through the coil 46 therebeneath, see Figure 2. Vertical reinforcing rods 50 have their ends welded to the rods 36 and 40, which vertical rods may be threaded through the convoluted wire coils of the web 44.

It will thus be seen that the plates 22 are effectively braced against lateral deflection by reason of the brace 34, and that all the plates between the spaced braces will be equally braced because of the transverse braces. Thus, I provide walls which are continuous and which lend a high degree of flexibility to the belt 12 because of the short plates which make up the walls. Accordingly, the plates are characterized by relative movement with their axes closely spaced so as to permit the belt 12 to bend easily and sharply about pulleys regardless of their diameters, and the plates pivot relatively to each other in either direction so as to provide a conveyor belt which bends equally well in either direction from its straight phase. The braces 34 perform an additional function in that they operate in the manner of cleats for goods and articles carried on the belt. The spacing between the braces or cleats will depend upon the requirements for which a given installation is designed.

While Figures 1 and 2 illustrate the brace 34 as being provided with a web 44, the brace may be in the nature of one or more transverse bars devoid of the web. Figure 3 illustrates two plates 52 corresponding to the plates 22, wherein two rods 54 have their ends welded to the inner faces of the plates 52 in lieu of the brace structure

illustrated in Figures 1 and 2. Plates 56 correspond to the plates 20 and each is provided with an elliptical opening 58 through which the rod 60 associated with the plates 52 is inserted, with the ends of the rod 60 subsequently welded at 62 to the outer faces of the plates 52.

Having thus described certain embodiments of my invention in detail, it is, of course, understood that I do not desire to limit the scope thereof to the exact details set forth except in so far as those details may be defined in the appended claims.

I claim:

1. A trough conveyor comprising a bottom of interlaced helical wires, walls extending along the sides of said bottom, each wall comprising plates arranged in overlapping relationship one with the other, each plate in each wall having an inner overlapping margin provided with an elongated opening having its major axis paralleling the straight phase of the bottom, said helical wires extending at right angles to said walls and transversely of said bottom, rods extending loosely through certain of said helical wires and loosely through said elongated openings, and connections between the ends of said wires and the outer overlapping margins of the plates in the respective walls.

2. A trough conveyor comprising a bottom of interlaced helical wires, walls extending along the sides of said bottom, each wall comprising plates arranged in overlapping relationship one with the other, each plate in each wall having an inner overlapping margin provided with an elongated opening having its major axis paralleling the straight phase of the bottom, said helical wires extending at right angles to said walls and transversely of said bottom, rods extending loosely through certain of said helical wires and loosely through said elongated openings, and connections between the ends of said wires and the outer overlapping margins of the plates in the respective walls, all the plates in each wall overlapping in the same order and sliding freely relatively to one another when said bottom of the conveyor is bent in either direction from its straight phase.

3. A trough conveyor comprising a bottom of interlaced helical wires, walls extending along the sides of said bottom, each wall comprising plates arranged in overlapping relationship one with the other, each plate in each wall having an inner overlapping margin provided with an elongated opening having its major axis paralleling the straight phase of the bottom, said helical wires extending at right angles to said walls and transversely of said bottom, rods extending loosely through certain of said helical wires and loosely through said elongated openings, connections between the ends of said wires and the outer overlapping margins of the plates in the respective walls, and brace cleats extending transversely of said bottom and interconnecting some of the plates in each wall with the corresponding plates in the other wall.

4. A trough conveyor comprising a bottom of interlaced helical wires, walls extending along the sides of said bottom, each wall comprising plates arranged in overlapping relationship one with the other, each plate in each wall having an inner overlapping margin provided with an elongated opening having its major axis paralleling the straight phase of the bottom, said helical wires extending at right angles to said walls and transversely of said bottom, rods extending loosely through certain of said helical wires

wires and loosely through said elongated openings, connections between the ends of said wires and the outer overlapping margins of the plates in the respective walls, all the plates in each wall overlapping in the same order and sliding freely relatively to one another when said bot-

tom of the conveyor is bent in either direction from its straight phase, and brace wires extending transversely of said bottom and interconnecting some of the plates in each wall with the corresponding plates in the other wall.

FREDERICK ROBBINS.
